UNITED STATES PATENT OFFICE

WILLIAM E. GHENT, OF ATLANTA, NEW YORK, ASSIGNOR TO BOGGS MANUFACTURING CORPORATION, OF ATLANTA, NEW YORK, A CORPORATION OF NEW YORK

WIRE BENDING MACHINE

Application filed June 17, 1932. Serial No. 617,824.

The present invention relates to a wire bending machine and has for its object to provide a machine of this class which can be manufactured at a relatively low cost and which is efficient in service and convenient to operate.

A further object of the invention is to provide an improved machine of the present type for bending wire to construct links formed of a plurality of loops for interengagement to afford chains or belts for different usages.

A further object of the invention is to provide in a machine of the class described improvements by which the size of the loops forming the links can be readily varied and in which the wire supporting parts are relatively adjustable to accommodate wires of different diameters or sizes.

To these and other ends the invention resides in certain improvements and combinations of parts, all as will be hereinafter more fully described, the novel features being pointed out in the claims at the end of the specification.

In the drawings:

Fig. 1 is a plan view illustrating one embodiment of the invention;

Fig. 2 is a front elevation of the same;

Fig. 3 is a fragmentary top plan view of the machine drawn to an enlarged scale showing the method of looping the wire about one of the forming elements;

Fig. 4 is a front elevation of the machine with the parts in the position shown in Fig. 3;

Fig. 5 is a sectional elevation taken substantially on the line 5-5 of Fig. 1;

Fig. 6 is a similar elevation with the front loop-forming lever moved to final operating position;

Fig. 7 is a fragmentary plan view showing the manner of positioning and supporting the end of the wire on which a loop of one size is to be formed when beginning a link of predetermined dimensions, and

Fig. 8 is a fragmentary plan view illustrating the series of connected links of a type constructed by use of the present machine.

The same reference numerals throughout the several views indicate the same parts.

The present machine is one having a plu-

rality of associated mandrels or forming elements for the series of loops which go to make up the links shown connected in Fig. 8. At least one of the forming elements is adjustable to provide for the construction of links having loops of different sizes. The forming elements are also relatively adjustable so that one may be adjusted to correspond to the adjustment of another. Furthermore the devices for supporting the wire in proper relation with respect to the forming elements are made adjustable for this purpose and are also adjustable one relative to another to accommodate wires of different diameters which may be employed in the construction of the links.

Referring to the drawings one example of the type of links formed on the present machine is shown in Fig. 8 in which the links each comprise a plurality of loops 10 with intermediate connecting portions overlying one another and forming additional loops 11 extending in the plane substantially at a right angle to the loops 10. When the links are connected as shown in Fig. 8, the vertical loops 11 of one link are centrally disposed with respect to the horizontal loops 10 of the next adjacent link and receive the latter, so that the openings formed by the loops 10 are in staggered relation as shown. When it is desired to construct a series of belts all of the same width but in which it is necessary to vary the size of the openings of the horizontal loops 10 within certain limits, this will require varying the number of the loops of the links for the different belts. This will result in different sized end loops at one or both ends of links having different numbers of loops. For example, where a belt of the desired width is formed of links having a given number of loops, every other link may have a half loop at each end, as indicated by the loop 12 in Fig. 8. However, for a different number of loops, the link may have the smaller or reduced size loop at one end only with a full size loop at its opposite end in which case the smaller loop of each link will be connected with the full sized end loop of the next succeeding link.

The present machine is designed to form

the horizontal and vertical loops 10 and 11 shown in Fig. 8, and to partially form the smaller end loops 12, as indicated at 12a in Fig. 7, the completion of this loop being 5 subsequently effected preferably on a different machine.

In the drawings 13 represents the base of the machine which is provided with one or more brackets 14 for attaching it to a suitable 10 support, not shown. The mandrel or forming element for the loops 10 preferably comprises two separate upstanding curved portions 15 and 16 carried respectively by the foot-like members 17 and 18 resting on the 15 base 13, and each having a slot 19 for receiving a clamping bolt 20 which extends through the base and serves to secure the parts in different adjusted positions, depending on the size of the loops to be formed by 20 bending the wire about the portions 15 and 16, as indicated in Fig. 3. This adjustment, it will be understood, permits the loop forming parts to be moved toward or from each other in order to reduce or increase the size 25 of the loops, as may be required.

The forming element for the vertical loops 11 comprises the part 21 which projects laterally from the upstanding portion 22 of a member 23, best shown in Figs. 3 and 4, and 30 forming a part of a lever supporting bracket. The remaining portion of the bracket comprises the upstanding part 24 carried by a member 25 upon which the portion 23 of the bracket rests. Portions 23 and 25 are slotted 35 at 26 to receive a bolt 27 extending through the base 13 and permitting the loop forming element 21 to be adjusted inwardly and outwardly to correspond to the adjustments of the upstanding loop forming element 15—16 40 when the latter is adjusted to vary the size of the loops 10. The lever 28 for bending the wire about the member 21 to form the vertical loop 11 has its inner end pivotally disposed between the upstanding portions 22 and 24 of the lever supporting bracket. The 45 lever carries a member 29 provided with an offset portion 30 having a groove 31 therein for receiving the wire when the lever is swung from the position shown in Fig. 5 to that 50 shown in Fig. 6.

The lever for bending the wire about the forming element 15—16 to produce the horizontal loops 10 is indicated at 32 and has its inner end resting on a support 33 on the base 55 13 and pivotally connected with a bolt 34 extending through the support and the base, as shown in Fig. 5. Adjustably secured on the lever is a member 35 having thereon an upstanding wire bending and positioning element 36, the wire engaging edge 37 of which is provided with a notch 38 for receiving the portion 10a of the wire when bending it about the elements 15—16, to form the loops 60 10. The edge 37 of the bending element 36 65 is preferably inclined a slight amount with

respect to the horizontal, as shown in Fig. 6, to facilitate downward movement of the wire into the notch 38 when the lever 32 is moved to operating position, as shown in Figs. 3 and 4, the notch being substantially in the plane 70 of the portion 11a of the wire as shown in Fig. 5. The part 35 carrying the wire bending element 36 is arranged to swing upon the lever 32 about the axis of a pivot bolt 39 whereby to adjust the wire bending element 75 to the proper angle with respect to the wire forming elements 15—16 in the different positions of adjustment thereof. When properly adjusted the member 35 is clamped in position by a bolt 40 extending through the lever and a slot 41 in said member, as shown in Fig. 1.

One of the members for supporting the wire during the bending operations comprises an angular shaped bracket having a horizontal portion 42 resting upon the base 13, and an upstanding portion 43 carrying a member for receiving and supporting the looped portions 11 of the wire, as shown in Figs. 3 and 4. The bracket is adjustable 85 upon the base toward and from the forming element 21 to accommodate the varying sizes of the loops 10, said bracket being held in the desired position by a bolt 45 extending through the base 13, Fig. 4.

Additional supporting means for the wire is provided in the form of a pair of screws 47 disposed adjacent the forming element 15—16 and threaded in the supporting members therefor indicated at 17 and 18, respectively. The lower ends of the screws are preferably extended within slots formed in the base 13, not shown, which permit the screws to be moved with the forming elements when the latter are adjusted to provide for the formation of loops of different sizes. Relatively fine adjustment of the screws can be easily effected by employing a screw driver to turn the same in order to obtain accurate distances in a vertical direction between the ends of the screws and the wire forming and supporting elements 21 and 44 respectively. These adjustments are made necessary in order to maintain the wire in proper relation with respect to other supporting parts therefor, and particularly the parts 21 and 44. Furthermore, when the size of the wire is to be increased or decreased the screws 47 will be adjusted accordingly, since it is preferred to maintain the supporting parts 21 and 44 at a fixed distance from the base 13. Furthermore, if desired, the size of the supporting pins 21 and 44 may be varied, depending on the diameter of the wire and the distance to be allowed between the upper and lower portions of the loops 11.

An additional support for the link is provided in the form of an adjustable screw 48 suitably mounted for vertical adjustment on the base, as for example by threading it 130

therein. This support can be spaced any desired distance from the forming elements 15—16, but is preferably so located as to form a rest for one of the side portions of the loop 10 carried by the supporting pin 44, as shown in Fig. 3. The height of the screw 48 will be regulated to correspond to that of the screws 47 in order to maintain the looped portion of the wire in the horizontal position as shown in Fig. 4.

When the first loop 10 of the link is to be made full size, as shown at the left of Fig. 3, the extreme end portion of the wire is bent to form a short hook-like portion 13a for receiving the half loop 12 of the next adjacent link, as shown in Fig. 8. After forming the hook-like portion the same is inserted upon the support 44 with the remaining portion of the wire extending over the base, as shown by dotted lines in Fig. 3, ready to be bent around the forming elements 15—16, as described hereinafter. However, if the first of the horizontal loops to be formed is to be of less width than the full size loop, as indicated by the half loop 12 in Fig. 8, the end 12a of the wire will be disposed in a notch 49 of a support 50 on a bracket 51 resting on the base 13 and slotted at 52 to receive a clamping bolt 53 extending through the base. Thus the bracket 30 is made adjustable in order that the position of the support 50 can be regulated to afford the proper angular relationship between the end 12a of the wire and the looped portion thereof, formed by bending the wire around the parts 15—16. As stated above, upon completion of the main loops the remaining portion 12a of the wire may be bent on a different machine to complete the half loop, as indicated at 12 in Fig. 8.

40 The member 28 and part 30 thereon for bending the wire about the member 21 to form the loops 11 is provided with a pivoted arm 54 having a hook 55 arranged when the lever is moved to the wire bending position shown in Fig. 6 to override the loop, under the resistance of the coil spring 56, which operates to yieldingly hold the hooked end of the arm in engagement with the forming element 15—16, the lever having a stop 57 for limiting the movement of the arm in one direction. The hook, therefore, when the lever is returning to normal position, will engage the loop 10 of the link and lift the latter from position upon the forming element 15—16, at which time the operator will shift it to the right to disengage it from the support 44 in order that it may be so adjusted as to place the loop 11, last formed by the operation of the lever 48, upon the support 44. After this adjustment of the wire is made the lever 32 will be operated from the position shown in Fig. 1 to that shown in Fig. 3 to cause the part 36 to engage and bend the wire about the forming element 15—16, as shown in Fig. 3. This operation serves to position the por-

tion 11a of the wire upon the support 47 and beneath the forming element 21, as shown in Fig. 5, where it is ready to be operated upon by the grooved part 30 of the lever 28 to form the next succeeding loop 11, these operations being continued until the loops of the link are completed. Upon moving the portion 11a of the wire to the full line position shown in Fig. 3, and then releasing it, this portion will assume the dotted line position shown in said figure, in which it will register with the groove 31 of the part 30 of the operating lever 28.

45 A support for the outer end of the lever is provided in the form of a semi-circular bar 54a overlying the base and spaced therefrom by suitable members 55a secured on the base. A spring 56, Fig. 2, serves to return the lever to normal position when released from the operating position shown in Fig. 3. The spring is wound upon an arbor 57, the upper end of which is journaled in the base and the lower end of which is journaled in a bracket 58 depending from the base. One end of the spring is attached to the arbor and the other to a suitable support 59 secured on the bottom of the base. The upper end of the arbor carries a sleeve 60 upon which rests one end of an arm 61 rigidly connected with the arbor. The arm is connected with a link 62 by means of a pivot member 63 which is free to travel in the slot 64 formed in the arm. The link is pivotally connected with a part 65 resting upon the member 35 on the lever 32, which carries the wire bending member 36, the part 65 being preferably secured by means of the bolt 39 connecting the member 35 with the lever 32.

50 When moving the lever 32 from normal to operating position the spring 56 becomes tensioned, through rotation of the arbor 57 upon which the spring is wound, and during this operation the link is free to shift upon the arm 61 from the position shown in Fig. 1 to that shown in Fig. 3. When the lever is released at operating position the spring will effect its rapid return to normal position at which it is arrested by a buffer 66 of rubber or other yieldable material secured on the support 54a in any suitable manner.

55 In the operation of forming the loops to produce the links, one end of the wire is provided with the bent portion 13a which is inserted upon the member 44 so that the wire will extend rearwardly over the base, as indicated by the dotted lines in Fig. 3, the wire at this time resting upon the head of the screw 47 carried by the member 17. The lever 32 is then moved from the position shown in Fig. 1, during which movement the inclined face 37 of the part 36 on the lever will engage the wire and facilitate depression of the same into the notch 38 of said part. Upon continued movement of the lever the wire will be bent around the forming ele-

ments 15—16 and will assume the full line position shown in Fig. 3, in which it is extended under the forming element 21 and over the screw 47 for supporting the same as shown in Fig. 5. Upon release of the lever for return to normal position the wire will assume the dotted line position shown in Fig. 3. The first horizontal loop 10 having thus been formed, the lever 28 is moved from the position shown in Fig. 5 to that shown in Fig. 6. In the upward movement of the lever the portion of the wire 11a adjacent the loop-forming element 21 will be received within the groove 31 of the part 30 on the lever and upon continued movement of the lever the wire will be bent about the element 21 to form the first vertical loop 11, as shown in Fig. 6. When the lever 28 is returned to normal position the hook 55 of the arm 54 will remove the loop 10 of the wire from the forming element 15—16, after which the operator will withdraw the wire from the parts 21 and 44 and will then shift it to the left, at the same time positioning the vertical loop 11 upon the support 44 and upon the screw 47 carried by the member 17. The levers 32 and 28 are then again operated in the manner described, these operations being continued until all of the loops have been formed.

30 The formation of the hook-like portion 13a on the last of the loops 10 to be completed may be formed by the use of any suitable means. The hook-like portion 13a of the first loop 10 may also be formed by said means after completion of all of the loops 10 if preferred, rather than in advance of the formation of the first loop.

Where the link is to be provided at one or both ends with the smaller loops 12 shown in Fig. 8, the end 12a of the wire will be positioned within the notch 49 of the support 50, as shown in Fig. 7, in which case the levers 32 and 28 will be operated in the manner described above to complete the full size loops 10. Subsequently the ends 12a of the wire will be bent by the use of suitable means to form the half or smaller size loops 12, as shown in Fig. 8.

I claim:

50 1. A machine for forming links from wire, comprising a base, a plurality of associated forming elements on the base, a manually operable device movable on the base to engage and bend the wire about one of said elements to form a loop having spaced side portions and serving during said bending operation to position the unbent portion of the wire in engagement with another of said elements, and means movable on the base to bend the wire about said last mentioned element to form a second loop at one side of the first mentioned loop.

60 2. A machine for forming links from wire, comprising a base, a plurality of associated forming elements on the base, supporting

means for the wire, a manually operable member pivoted on the base and operable to bend the wire about one of said elements to form a loop having spaced side portions and serving to position the unbent portion of the wire in engagement with another of the forming elements, and a second member operable to bend the wire about said last mentioned element to form with one of said side portions a second loop in a plane at an angle to the plane of the first mentioned loop. 70 75

3. A machine for forming links from wire, comprising a base, a plurality of associated forming elements on the base, supporting means for the wire, a lever pivoted on the base and operable to bend the wire about one of said elements to form a loop having spaced side portions and serving to position the unbent portion of the wire in engagement with another of said forming elements, a second lever operable to bend the wire about said last mentioned element to form with one of said side portions a second loop in a plane at an angle to the plane of the first mentioned loop, and a part on the last mentioned lever arranged to withdraw one of the loops from its forming element when said lever is returned to normal position. 80 85 90

4. A machine for forming links from wire, comprising a base, a plurality of associated forming elements on the base, supporting means for the wire, a lever pivoted on the base and operable to bend the wire about one of said elements to form a loop having spaced side portions, a second lever operable to bend the wire about another of said elements to form with one of said side portions a second loop in a plane at an angle to the plane of the first mentioned loop, a spring pressed arm pivoted on said last mentioned lever and having a part thereon arranged to override a portion of the first mentioned loop when the second lever is moved to operating position, said part serving when the second lever is returned from operative to inoperative position to withdraw one of the loops from its forming element. 95 100 105 110

5. A machine for forming links from wire, comprising a base, a plurality of associated forming elements on the base, a lever pivoted on the base and movable from normal inoperative position to bend the wire about one of said elements to form a loop having spaced side portions, linkage means connected with said lever, operating means arranged to move the linkage means to effect return of said lever to normal position, and a second lever operable to bend the wire about another of said forming elements to form with one of the side portions of said loop a second loop extending in a plane at an angle to the plane of the first mentioned loop. 115 120 125

6. A machine for forming links from wire, comprising a base, a plurality of associated forming elements on the base, a lever

mounted to swing upon the base and having a laterally extending offset part thereon arranged when the lever is moved from normal to a predetermined position to engage and bend the wire about one of said elements to form a loop having spaced side portions, means for returning said lever to normal position when released, and a second lever operable to bend the wire about another of said elements to form with one of said side portions a second loop in a plane at an angle to the plane of the first mentioned loop.

7. A machine for producing links from wire by successively looping the wire to complete the links, comprising a base, associated forming elements on the base, means on the base comprising relatively adjustable parts for supporting wire of different diameters each in a predetermined relationship with respect to said forming elements, a device movable on the base to loop the wire about one of said elements and to position it for a bending operation about another of said elements, and a second device movable upon the base arranged to engage and bend the wire about the last mentioned forming element, said wire being shiftable upon the supporting means following the successive operations of said devices for subsequent bending operations by said devices to duplicate said looping and bending operations.

8. A machine for producing links from wire, by looping the wire to successively form the links, comprising a base, associated forming elements on the base, means for supporting the wire in a predetermined relation with respect to said forming elements, a lever mounted to swing on the base and having a part arranged to loop the wire about one of said elements and to position it for a bending operation about another of said elements, and a second lever movable on the base arranged to engage and bend the wire to form a second loop thereon, said wire being shiftable upon the supporting means following the successive operations of said levers for subsequent bending by the levers to duplicate said loops.

9. A machine for producing links from sections of wire by looping the sections to successively complete the links, comprising a base, a loop forming device on the base including relatively adjustable parts for varying the size of the loops, means on the base for supporting the wire adjacent said device, a second loop forming device on the base, a member movable upon the base to loop the wire about one of said devices, and a second member movable on the base arranged to bend the wire about another of said devices, said wire being shiftable upon the supporting means following the successive bending operations of said members for subsequent bending operations by said members to duplicate the loops.

10. A machine for producing links from sections of wire by looping the sections to successively complete the links, comprising a base, a loop forming device on the base including relatively adjustable parts for varying the size of the loops, relatively adjustable parts on the base for supporting the wire adjacent said device, a second loop forming device adjustable on the base to different positions corresponding to the adjustments of the parts of said last mentioned device, a member movable upon the base to loop the wire about one of said devices, and a second member movable upon the base arranged to bend the wire about the other of said devices, said wire being shiftable upon said supporting parts following the successive operations of said members for subsequent bending operations by said members to duplicate the loops.

11. A machine for producing wire links having loops of different sizes comprising a base, associated elements on the base for forming the loops, one of said elements comprising relatively adjustable parts for varying the size of the loops, another of the elements being adjustable to correspond to the adjustments of the last mentioned element, means movable on the base to bend the wire about one of said elements to form one loop, and means on the base operable to bend the wire about another of the elements to form a different loop.

12. A machine for producing wire links having loops of different sizes comprising a base, associated elements on the base for forming the loops, one of said elements comprising relatively adjustable parts for varying the size of the loops, another of the elements being adjustable to correspond to the adjustments of the last mentioned element, an adjustable device on the base for holding the wire in predetermined position relative to said elements, means movable on the base to bend the wire about one of said elements to form one loop, and means on the base operable to bend the wire about another of the elements to form a different loop.

13. A machine for producing wire links having loops of different sizes comprising a base, associated elements on the base for forming the loops, one of said elements comprising relatively adjustable parts for varying the size of the loops, another of the elements being adjustable to correspond to the adjustments of the last mentioned element, means movable on the base to bend the wire about one of said elements to form one loop, and a lever pivotally connected with another of said elements and operable to bend the wire about the same to form a different loop.

14. A machine for producing links from sections of wire by successively looping the wire to complete the links, comprising a base, associated loop forming devices on the base,

- relatively adjustable parts for supporting the wire in predetermined relationship with respect to one of said loop-forming devices in advance of and during the looping operations, means movable on the base to bend the wire about one of said elements to form one loop, and means on the base operable to bend the wire about another of the elements to form a different loop.
- 10 15. A machine for producing links from sections of wire having different diameters by bending the wire to successively form the loops, comprising a base, associated loop forming elements on the base, spaced supporting devices for holding the wire in a predetermined position with respect to said loop forming elements, one of said devices being adjustable relative to another to accommodate wires of different diameters, means 15 for bending the wire about one of said elements to form one loop, and means for subsequently bending the wire about another of said elements to form a different loop.
16. A machine for producing wire links having loops of different sizes, comprising a base, associated elements on the base for forming the loops, one of said elements comprising relatively adjustable parts for varying the size of the loops formed thereon, 20 another of the elements being adjustable to correspond to the adjustments of the last mentioned element, a supporting member on the base for the wire, additional supporting members on the base adjustable relative to 25 the last mentioned member to maintain the wire in predetermined relationship with respect to said elements during the loop forming operations, a lever movable upon the base to loop the wire about one of said elements, and a second lever on the base for bending the wire about another of the elements to 30 form a different loop.
17. A machine for producing wire levers having loops of different sizes, comprising a base, associated elements on the base for forming the loops, one of said elements comprising relatively adjustable parts for varying the size of the loops formed thereon, a supporting member on the base for the wire, 35 screws carried by and adjustable upon said parts to form additional supporting means for holding the wire in predetermined relationship with respect to said parts, a lever operable upon the base to loop the wire about one of said elements, and a second lever on the base for bending wire about another of the elements to form a different loop.
- 40 45. A machine for producing wire links having loops of different sizes, comprising a base, associated elements on the base for forming the loops, one of said elements comprising relatively adjustable parts for varying the size of the loops to be formed thereon, another of the elements being adjustable on 45 the base to maintain it in predetermined relationship with respect to the last mentioned element, a supporting device for the wire adjustable upon the base to different positions to correspond to the different sizes of the loops to be formed on said adjustable element, additional supporting devices for the wire adjustable upon the base to accommodate wires having different diameters, a lever on the base for looping the wire about one of said elements, and a second lever on the base for bending the wire about another of the elements to form a different loop.
- 50 55. A machine for bending a single piece of wire to form a link having a series of integrally connected sections, comprising a base, a plurality of associated forming mandrels on the base, a device for bending the wire about one of the mandrels to form a portion of one section, and a separate device for bending the wire about a second mandrel to form another portion of the section while said first portion remains in bent position upon its mandrel, said sections being successively produced by shifting the wire after the forming of each section to place the unbent portion of the wire in position to be bent about the first mandrel and subsequently about the second mandrel by the bending devices corresponding to said mandrels.
- 60 65. A machine for bending a single piece of wire to form a link having a series of integrally connected sections, comprising a base, a plurality of associated forming mandrels on the base, a device for bending the wire about one of the mandrels to form a portion of one section and serving during said bending operation to position the unbent portion of the wire in engagement with a second mandrel, and a separate device for bending the wire about said second mandrel to form another portion of the section while said first portion remains in position upon its mandrel, said sections being successively produced by shifting the wire after the forming of each section to place the unbent portion of the wire in position to be bent about the first mandrel and subsequently about the second mandrel by the bending devices corresponding to said mandrels.
- 70 75. A machine for bending a single piece of wire to form a link having a series of integrally connected sections, comprising a base, a plurality of associated forming mandrels on the base, a device for bending the wire about one of the mandrels to form a portion of one section and serving during said bending operation to position the unbent portion of the wire in engagement with a second mandrel, and a separate device for bending the wire about said second mandrel to form another portion of the section while said first portion remains in position upon its mandrel, said sections being successively produced by shifting the wire after the forming of each section to place the unbent portion of the wire in position to be bent about the first mandrel and subsequently about the second mandrel by the bending devices corresponding to said mandrels.
- 80 85. A machine for bending a single piece of wire to form a link having a series of integrally connected sections, comprising a base, a plurality of associated forming mandrels on the base, a device for bending the wire about one of the mandrels to form a portion of one section and serving during said bending operation to position the unbent portion of the wire in engagement with a second mandrel, and a separate device for bending the wire about said second mandrel to form another portion of the section while said first portion remains in position upon its mandrel, said sections being successively produced by shifting the wire after the forming of each section to place the unbent portion of the wire in position to be bent about the first mandrel and subsequently about the second mandrel by the bending devices corresponding to said mandrels.
- 90 95. A machine for bending a single piece of wire to form a link having a series of integrally connected sections, comprising a base, a plurality of associated forming mandrels on the base, a device for bending the wire about one of the mandrels to form a portion of one section and serving during said bending operation to position the unbent portion of the wire in engagement with a second mandrel, and a separate device for bending the wire about said second mandrel to form another portion of the section while said first portion remains in position upon its mandrel, said sections being successively produced by shifting the wire after the forming of each section to place the unbent portion of the wire in position to be bent about the first mandrel and subsequently about the second mandrel by the bending devices corresponding to said mandrels.
- 100 105. A machine for bending a single piece of wire to form a link having a series of integrally connected sections, comprising a base, a plurality of associated forming mandrels on the base, a device for bending the wire about one of the mandrels to form a portion of one section and serving during said bending operation to position the unbent portion of the wire in engagement with a second mandrel, and a separate device for bending the wire about said second mandrel to form another portion of the section while said first portion remains in position upon its mandrel, said sections being successively produced by shifting the wire after the forming of each section to place the unbent portion of the wire in position to be bent about the first mandrel and subsequently about the second mandrel by the bending devices corresponding to said mandrels.
